RAILWAY TRAFFIC CONTROLLING APPARATUS

Original Filed May 5, 1926

UNITED STATES PATENT OFFICE

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Original application filed May 5, 1926, Serial No. 106,871. Divided and this application filed August 5, 1929. Serial No. 383,733.

My invention relates to railway traffic controlling apparatus, and particularly to apparatus comprising governing means controlled by energy in the track rails. More particularly my present invention relates to the means for supplying such energy to the rails.

One purpose of my invention is the provision of novel means for supplying energy to the track rails so that uninterrupted alternating current is normally supplied to the rails, but that under certain conditions periodically interrupted alternating current is supplied to the rails, the characteristic of these periodic interruptions being controlled in accordance with traffic conditions.

The present application is a division of my copending application Serial No. 106871, filed May 5, 1926, for railway traffic controlling apparatus.

I will describe one form of trackage apparatus embodying my invention, and will then point out the novel features thereof in claims.

The accompanying drawing is a diagrammatic view illustrating one form of trackway apparatus embodying my invention as applied to a stretch of track over which traffic moves in both directions.

Referring to the drawing, the reference characters 1 and 1^a designate the track rails of a stretch of railway track over which traffic normally moves in both directions. These track rails are divided, by means of insulated joints 2, into a plurality of successive track sections, A—B, B—C, etc.

Each track section is provided with a track relay designated by the reference character R with an exponent corresponding to the location, and comprising two windings 6 and 7. Winding 6 of each track relay is constantly connected across the rails adjacent the right hand end of the associated section, and winding 7 is constantly supplied with alternating current from terminals a and b of a suitable source of alternating current not shown in the drawing. Each track section is supplied with alternating current from a track transformer

designated by the reference character T with an exponent corresponding to the location, and comprising a secondary 3 constantly connected across the rails adjacent the left hand end of the section in series with the usual impedance 5. The supply of alternating current to the primary 4 of each track transformer T is controlled by a repeater relay located at the left hand end of the section and designated by the reference character P with an exponent corresponding to the location. Each repeater relay is controlled by the track relay for the same section. Referring, for example, to the repeater relay P^A, it will be seen that when relay R^B is energized, current flows from one terminal a of a suitable source of current, through contact 218 of relay R^B, and the winding of relay P^A to the other terminal b of the same source. When relay R^B is de-energized, however, this circuit for relay P^A is open and the relay becomes de-energized. Primary 4 of each track transformer T is normally supplied with alternating track circuit current from the terminals a and b through the front point of contact 191 of the associated repeater relay P.

Each track section is further provided with two line relays designated by the reference characters 158 and 159 with exponents corresponding to the location. Each track section is also provided with two stick relays designated by the reference characters 160 and 161 with appropriate distinguishing exponents. Referring particularly to line relay 159^B, this relay is provided with two circuits, one of which passes from terminal a, through wire 162, front contact 163 of line relay 159^C, wires 164 and 165, front contact 166 of relay R^C, wire 167, winding of relay 159^B, wire 168, front contact 169 of relay P^B, wire 170 and back contact 171 of relay 160^B to terminal b. This circuit is closed only when relay 160^B is de-energized and when relays P^B, R^C and 159^C are all energized. When relay 161^C is energized, a second circuit is closed for relay 159^B from terminal a, through front contact 173 of relay 161^C, wires 174 and 165, front contact 100

- 166 of relay R^c , wire 167; winding of relay 159^b, wire 168, front contact 169 of relay P^b , wire 170, and back contact 171 of relay 160^b to terminal *b*. The control of each of 5 the remaining line relays 159 and 158 is similar to that just explained for relay 159^b and will be understood from the drawing without tracing the circuit for these relays in detail.
- 10 Stick relay 161^b is provided with a pick-up circuit which passes from terminal *a*, through wire 175, back contact 176 of relay 158^b, wire 177, back contact 178 of relay R^b , wire 179, back contact 180 of relay P^b , wire 181, front contact 182 of relay 159^b, wires 183 and 184, and winding of relay 161^b to terminal *b*. Relay 161^b, having been energized over the pick-up circuit just traced, is maintained in its energized condition as 20 long as relay 159^b is de-energized, the stick circuit being from terminal *a*, through wire 185, back contact 186 of relay 159^b, wire 187, front contact 188 of relay 161^b, wires 189 and 184, winding of relay 161^b and back to 25 terminal *b*. The remaining relays 161 and 160 are each provided with circuits similar to those just traced for relay 161^b.
- The control of line relays 158 and 159 and the stick relays 160 and 161 is similar to the 30 control of these relays in the usual and well known absolute permissive block signaling systems, and their operation will be readily understood by those skilled in the art. For example, one system embodying line relays 35 and stick relays controlled in this manner is disclosed in Letters Patent of the United States No. 1,602,137, granted to me on October 5, 1926, for railway traffic controlling apparatus.
- 40 Located at the junction of each two adjoining sections is a coding device designated by the reference character K with an exponent corresponding to the location. Each of these devices comprises two magnets 8 and 9 and a pivoted armature 49 biased to a central position but arranged to be attracted by one or the other of the magnets. Carried by the armature 49 are movable contacts 11, 14, 33 and 190, which swing to one side or 45 the other depending upon which of the magnets 8 or 9 is attracting the armature. Referring particularly to coding device K^b , this device is provided with a circuit including back contact 219 of relay P^b and back 50 contact 218 of relay R^b in multiple, so that this device will be energized when either section A—B or B—C is occupied by a train. The devices K are intended to operate on direct current, and since these devices are 55 supplied with alternating current from the terminals *a* and *b*, a rectifier 10 is included in the circuit for each device K to change the alternating current supplied thereto to unidirectional current. It will be seen that 60 contact 11—11^a is arranged to short circuit magnet 9, and contact 11—11^b is arranged to short circuit magnet 8. The contacts are so arranged that when the device is de-energized contact 11—11^a is closed. If therefore, the energizing circuit becomes closed, 70 current supplied to the device will flow through magnet 8, but will be shunted around magnet 9 by contact 11—11^a. Armature 49 will therefore be attracted by magnet 8 to open contact 11—11^a and close contact 11—11^b. Current will then be supplied to magnet 9, and magnet 8 will be short circuited. The magnets 8 and 9 are arranged to be slow acting however, so that an interval of time will elapse before the increasing 80 flux in magnet 9 will overcome the decreasing flux in magnet 8 to a sufficient degree to again reverse armature 49. At the expiration of this time interval armature 49 will swing back toward magnet 9 and contact 11—11^b will be opened and contact 11—11^a will be closed. Another time interval will 85 then elapse before armature 49 is again reversed. It follows that as long as the circuit for device K is closed, the armature 49 will oscillate so that the contacts controlled by the armature are operated intermittently. The contacts 14—14^a and 14—14^b are so adjusted that these contacts are both closed 90 when the device is de-energized. When the device is energized however, these contacts are opened alternately. The parts are so arranged, as indicated by the unequal shunting bands on the magnets 8 and 9, that when the device K is operated contact 100 14—14^a is closed for a larger proportion of each cycle than is contact 14—14^b. For example, assuming that a complete cycle of operation of the device requires one second, the contacts may be so arranged that contact 105 14—14^a is closed for two-thirds of a second, and contact 14—14^b is closed for one-third of a second. This adjustment to accomplish unequal timing of the contacts or "limping," 110 may be effected by suitable adjustments in the structure of the device or in the positions of the contact members.
- As shown in the drawing, the stretch of tract is unoccupied and all track relays R , and hence all repeater relays P , are energized, current being supplied to the rails of each section from the associated transformer T . All line relays 158 and 159 are also energized, and all stick relays 160 and 161 are de-energized. Coding devices K 115 are also de-energized.
- To explain the operation of the apparatus, I will first assume that a train travelling from left to right passes through the stretch of track shown in the drawing. The presence of this train in the section to the left of point A will de-energize relay R^A , and therefore relay 158^a will be de-energized. The de-energization of relay 158^a will interrupt the circuit for relay 158^b, and the open- 120

ing of relay 158^B will interrupt the circuit for relay 158^C. When the train enters section A—B, relay R^B will become de-energized, thereby opening the circuit for relay 5 P^A. The closing of back contact 180 of this relay will close the pick-up circuit for relay 161^A. At the same time, the opening of front contact 169 of relay P^A will open the circuit for relay 159^A, and after an interval 10 of time due to its slow acting characteristics the relay 159^A will open. When this happens, the pick-up circuit for relay 161^A will be opened, but the relay will be held in its energized condition by its stick circuit over back contact 186 of relay 159^A. The line relay 159^A being slow acting, it is insured that a sufficient time will elapse after the closing of back contact 180 of relay P^A, 15 for relay 161^A to become fully energized. 20 The closing of back contact 218 of relay R^B will set device K^B into operation, and current will then be periodically supplied to primary 36 of a transformer L^B having its secondary 35 connected across the rails adjacent the right hand end of section A—B. The circuit for transformer L^B may be traced from terminal *a*, through wire 192, contact 33—33^a of device K^B, wire 193, front contact 194 of relay 159^B, wire 195, back contact 25 196 of relay R^B, wire 197, and primary 36 of transformer L^B to terminal *b*. When this circuit is closed, current will be supplied to the rails of section A—B by transformer L^B in accordance with what I will term proceed 30 code. When the train enters section B—C, relays R^C and P^B will open, relay 161^B will pick up, and relay 159^B will open, completing the stick circuit for relay 161^B. The closing of back contact 218 of relay R^C 35 will set coding device K^C into operation, and current will therefore be supplied over contact 33—33^a of device K^C to primary 36 of transformer L^C, so that current will be supplied to the rails of section B—C in accordance with the proceed code. After 40 the train moves out of section A—B, alternating current supplied to the rails of the section by transformer T^A will energize relay R^B, thereby energizing relay P^A and opening back contact 218. Device K^B will still operate however, its circuit then being closed at back contact 219 of relay P^B. Current will then be supplied to the rails by transformer T^A, and transformer L^B will 45 be de-energized. Relay 159^A will also become energized, its circuit being closed over front contact 173 of relay 161^B, and front contact 166 of relay R^B. The opening of back contact 186 of relay 159^A will de-energize relay 161^A and will return the apparatus to its normal condition. The operation 50 of the apparatus when the train moves out of section B—C will be understood from the foregoing without further explanation. 55 C5 I will assume that a train is in the sec-

tion to the right of point C, so that relays P^C and 159^C are de-energized, and relay 161^C is energized. Device K^C is of course energized, but uninterrupted current is being supplied to the rails of section B—C from transformer T^B and the supply of current to transformer L^C is interrupted at back contact 196 of relay R^C, now open. I will next assume that a second train also moves from left to right, entering the stretch of track shown in the drawing. The operation of the apparatus associated with section A—B in response to the movement of this second train through the section is the same as described in connection with the first train, 70 and will be understood without further explanation. When the second train enters section B—C, the de-energization of relays R^C and P^B will de-energize relay 159^B as before, and relay 161^B will become energized, but current will then be supplied to section B—C from an auxiliary transformer Q^C having its secondary 29 connected across the rails at an intermediate point in the section. The circuit for the 75 primary 30 of transformer Q^C may be traced from terminal *a*, through contact 33—33^b of device K^C, wire 198, front contact 199 of relay 161^C, wire 200, back contact 201 of relay R^C, wire 202, and primary 30 of transformer Q^C to terminal *b*. The rails of section B—C will therefore be supplied with interrupted alternating current in accordance with what I will term the caution code from transformer Q^C. The following train 80 will therefore receive a caution indication between point B and the point of connection of transformer Q^C, and a stop indication between the latter point and point C because of the absence of train governing 85 current. 90 I will next assume that a train moving from right to left passes through the stretch of track shown in the drawing. The entrance of the train into the section to the right of point C will de-energize relays P^C and 159^C. Relays 159^B and 159^A will therefore be de-energized, all relays 158 will be energized and all relays 160 and 161 will be de-energized. When the train enters section B—C, the de-energization of relays R^C and P^B will pick up relay 160^C and will de-energize relay 158^C to close the stick circuit for relay 160^C. The closing of back contact 219 of relay P^B will set device K^B 95 into operation, and current will then be supplied to transformer T^B from terminal *a*, through wire 204, contact 14—14^a of device K^B, wire 205, front contact 206 of relay 158^B, wire 207, back contact 191 of relay P^B, wire 100 208 and primary 4 of transformer T^B to terminal *b*. Under these conditions therefore the train in section B—C will be supplied with current according to the proceed code from transformer T^B. 105 110 115 120 125 130

When the train enters section A—B, the apparatus associated with this section will operate in the same manner as just described in connection with section B—C, and the train will receive a proceed indication throughout the section. When the train moves out of section B—C, relays R^c and P^b will become energized, and relay 158^c will pick up over front contact 222 of relay 160^b. Current will then be supplied to transformer T^b over a circuit which passes from terminal *a*, through wire 216, back contact 206 of relay 158^b, wire 207, back contact 191 of relay P^b, wire 208 and primary 15 4 of transformer T^b to terminal *b*. By virtue of the circuit just traced uninterrupted current will be supplied to the rails of section B—C by transformer T^b. Means are provided, however, for at times interrupting 20 this current to give a caution code to a second train entering a section when the section in advance is occupied by a train moving in the same direction. For this purpose each track section is provided with an 25 auxiliary transformer, designated by the reference character Y with an exponent corresponding to the location, and having its primary 156 connected across the rails at an intermediate point in the section. Referring particularly to transformer Y^b, the secondary of this transformer is provided with a circuit which may be traced from the right hand terminal of secondary 157, through wire 210, contact 190—190^a of device 30 K^b, wire 211, front contact 212 of relay 160^b, wire 213, back contact 214 of relay P^b and wire 215 back to the left hand terminal of secondary 157 of transformer Y^b. When this circuit is closed the secondary of 35 transformer Y^b is short circuited and is effective to shunt the rails at the point of connection of the transformer so that the current between transformer Y^b and point C is shunted. It follows that when the circuit is being periodically closed by contact 190—190^a of device K^b, the rails of section B—C between the point of connection of 40 transformer Y^b and point C are being supplied with current in accordance with the caution code. The second train will therefore receive a caution indication between point C and transformer Y^b and a stop indication between transformer Y^b and point B. 45 Attention should be directed to the fact that if a train attempts to traverse the stretch of track in one direction when the stretch is already occupied by a train moving in the other direction, it will receive a stop indication. For example, I will assume that a train moving from right to left occupies section B—C. Relays P^b and R^c are de-energized and all relays 159 are de-energized. Relay 50 158^c is also de-energized but relay 160^c is energized. If, now, a train moving from

left to right enters section A—B, the consequent de-energization of relay R^b will not close the code circuit for primary 36 of transformer L^b because this circuit will be transferred at front contact 194 of relay 55 159^b. Similarly, the circuit for primary 30 of transformer Q^b will be open at front contact 199 of relay 161^b. The train in section A—B therefore can receive no interrupted alternating current from a point in 60 advance of the train and a stop indication will therefore be received by the train. 75

In similar manner, if a train moving from left to right occupies section A—B, so that relays P^a and R^b are de-energized, relays 80 158 will all be de-energized, relay 159^a will be de-energized, and relay 161^a will be energized. I will now assume that a train moving from right to left enters section B—C. The resulting de-energization 85 of relay P^b will complete a circuit for transformer T^b over back contact 191 of relay P^b and back contact 206 of relay 158^b, so that uninterrupted alternating current will be supplied to the rails of section B—C by transformer T^b. The shunting circuit for 90 transformer Y^b will be open at front contact 212 of relay 160^b which will then be open, and the current supplied to the rails of section B—C therefore cannot be interrupted. The uninterrupted current which the train in section B—C receives will give 95 a stop indication aboard the train. 100

It should be pointed out that the trackway apparatus here shown and described is suitable for, though in no way limited to, use in connection with train carried governing means forming no part of my present invention and omitted from the drawing for the sake of simplicity. For present purposes it is sufficient to state that when the portion of track occupied by the train is supplied with code impulse combinations in accordance with the proceed code, a proceed indication is received on board 105 the train; when the portion of track which is occupied by the train is supplied with code impulse combinations in accordance with the caution code, a caution indication is received on board the train; and when the rails occupied by the train are supplied with uninterrupted alternating current or with no current, the train receives a stop indication. 110

Although I have herein shown and described only one form of trackway apparatus embodying my invention, it is understood that various changes and modifications may be made therein within the scope of the appended claims without departing from 115 the spirit and scope of my invention. 120

Having thus described my invention, what I claim is:

1. In combination, a stretch of railway track, means for normally supplying unin- 130

6 interrupted alternating current to the rails adjacent one end of the stretch, and means controlled by traffic conditions for at times periodically interrupting said current and for at other times supplying interrupted current to the rails adjacent the other end of the stretch.

7. In combination, a stretch of railway track over which traffic moves in both directions, means for normally supplying alternating current to the rails adjacent one end of the stretch, means effective when a train moving in one direction occupies such stretch for periodically interrupting said current or for periodically shunting the rails depending upon traffic conditions in advance of such train, and means effective when a train moving in the opposite direction occupies such stretch for supplying interrupted current to the rails in advance of such last mentioned train.

8. In combination, a stretch of railway track over which traffic moves in both directions, means for normally supplying alternating current to the rails adjacent one end of the stretch, means effective when a train moving in one direction occupies such stretch for periodically interrupting said current or for periodically shunting the rails depending upon traffic conditions in advance of such train, and means effective when a train moving in the opposite direction occupies such stretch for supplying interrupted current to the rails in advance of such last mentioned train so that current flows in the rails for different proportions of a given interval of time depending upon traffic conditions.

9. In combination, a stretch of railway track over which traffic moves in both directions, means for normally supplying alternating current to the rails adjacent one end of the stretch, means effective when a train moving in one direction occupies such stretch for periodically interrupting said current, and means effective when such stretch is occupied by a train moving in the opposite direction for supplying interrupted current to the rails adjacent the other end of the stretch.

10. In combination, a stretch of railway track over which traffic moves in both directions, means for normally supplying uninterrupted alternating current to the rails of the stretch, and means effective when the stretch is occupied by a train moving in either direction for supplying the rails in advance of such train with interrupted current in accordance with traffic conditions in advance of the train.

11. In combination, a stretch of railway track over which traffic moves in both directions, means for normally supplying uninterrupted alternating current to the rails of the stretch, and means effective when the

stretch is occupied by a train moving in either direction for supplying the rails in advance of such train with interrupted current so that the train is supplied with current for different proportions of a given interval of time depending upon traffic conditions.

12. In combination, a stretch of railway track, means for normally supplying uninterrupted alternating current to the rails adjacent one end of the stretch, means for at times periodically interrupting said current, and means for at times supplying interrupted current to the rails adjacent the other end of the stretch.

13. In combination, a stretch of railway track, means for normally supplying uninterrupted alternating current to the rails adjacent one end of the stretch, means for at times periodically interrupting said current, and means for at times supplying interrupted current to the rails adjacent the other end of the stretch or at an intermediate point in the stretch depending upon traffic conditions.

14. In combination, a stretch of railway track, means for normally supplying uninterrupted alternating current to the rails adjacent one end of the stretch, means for at times periodically interrupting said current, and means for at times supplying interrupted current to the rails at other points in the stretch so that such current flows in the rails for different proportions of a given interval of time depending upon traffic conditions.

15. In combination, a stretch of railway track, means for normally supplying uninterrupted alternating current to the rails adjacent one end of the stretch, means for at times periodically interrupting said current, means effective under certain traffic conditions for supplying interrupted current to the rails adjacent the other end of the stretch so that such current flows in the rails for one proportion of a given interval of time, and means effective under other traffic conditions for supplying interrupted current to the rails at an intermediate point in the stretch so that current flows in the rails for a different proportion of said interval of time.

16. In combination, a stretch of railway track over which traffic moves in both directions, means for normally supplying uninterrupted alternating current to the rails adjacent one end of the stretch, means effective when a train moving in one direction occupies the stretch for periodically interrupting said current to give one code if conditions in advance of such train are safe and for periodically shunting the rails at an intermediate point in the stretch to give a second code if conditions in advance of the train are unsafe, and means effective

- when the stretch is occupied by a train moving in the opposite direction to supply the rails adjacent the opposite end of the stretch with interrupted current to give said 5 one code if conditions in advance of the train are safe and to supply the rails at a second intermediate point in the stretch with interrupted current to give said second code if conditions in advance of the 10 train are unsafe.
12. In combination, a right hand and a left hand section of railway track over which traffic moves in both directions, means for normally supplying uninterrupted alternating current to the rails adjacent the left hand end of each section, a single coding relay, and means including said coding relay for at times interrupting the supply of current to the right hand section, and for 15 at other times supplying interrupted alternating current to the rails of said left hand section.
13. In combination, a stretch of railway track over which traffic moves in both directions, means effective when a train moving in one direction occupies such stretch for periodically interrupting said current or for periodically shunting the rails depending upon traffic conditions in advance of 20 such train, and means effective when a train moving in the opposite direction occupies such stretch for supplying interrupted current to the rails in advance of such last mentioned train.
14. In combination, two adjoining sections of railway track, means including a single normally de-energized electric motor for supplying periodically interrupted train governing current to the rails of each 25 section at the end adjacent to the other section, and means for energizing said motor when either of said sections is occupied by a train.
15. In combination, two adjoining sections of railway track, a single normally de-energized electric motor for said two sections, means including contacts operated by said motor for supplying periodically interrupted train governing current to the rails of each 30 section at the end adjacent to the other section, and means for energizing said motor when either of said sections is occupied by a train.
16. In combination, two adjoining sections of railway track, means including a single normally de-energized electric motor for supplying periodically interrupted train governing current to the rails of each section at the end adjacent to the other section, a track circuit including a track relay for each of said sections, and means for energizing said motor when either of said track 35 relays is open.
17. In combination, two adjoining sections of railway track, a single normally de-energized electric motor for said two sections, means including contacts operated by said motor for supplying periodically interrupted train governing current to the rails of each section at the end adjacent to the other section, a track circuit including a track relay for each of said sections, and means for energizing said motor when either of said track relays is open.
18. In combination, two adjoining sections of railway track, a single normally de-energized electric motor for said two sections, means including contacts operated by said motor for supplying train governing current to the rails of each section at the 40 end adjacent the other section which current is periodically interrupted in accordance with one code or another depending on traffic conditions in the other section, and means for energizing said motor when either of said sections is occupied by a train.
19. In combination, a stretch of railway track divided into sections; absolute-permissive block signaling apparatus for said stretch involving the usual track relays, line relays and stick relays; and means for supplying train governing current to the rails at each end of each section periodically interrupted in accordance with one code when the associated line relay is closed and in accordance with a different code when the associated line relay is open but the associated stick relay is closed.
20. In combination, a stretch of railway track divided into sections; absolute-permissive block signaling apparatus for said stretch involving the usual track relays, line relays and stick relays; a coding device located at the junction of each two adjacent sections and comprising a normally de-energized motor as well as two contacts operated thereby in accordance with two different codes, means operating when a section is occupied by a train to energize the motor for the coding device at each end of the section, and means for supplying train governing current to the rails at each end of each section through one contact of the associated coding device when the associated line relay is closed and through the other contact of such coding device when the associated line relay is open and the associated stick relay is closed.
21. In combination, a stretch of railway track divided into sections, a track circuit including a track relay for each section, a line relay for each section for governing traffic in one direction through the section, means for controlling each line relay by the track relay for the section next in advance in the said direction and by the line relay for such section next in advance, a normally de-energized stick relay for each section, means for energizing each stick relay while a train moving in the said one direction but

not in the other occupies the associated section, means operating when each stick relay is energized to remove the associated line relay from its control of the line relay for the section next in the rear, and means for supplying train governing current to the rails of each section at each end of each section through one contact of the associated coding device when the associated line relay is closed and through the other contact of such coding device when the associated line relay is open and the associated stick relay is closed.

22. In combination, a stretch of railway track divided into sections, a track circuit including a track relay for each section, a line relay for each section for governing traffic in one direction through the section, means for controlling each line relay by the track relay for the section next in advance in the said direction and by the line relay for such section next in advance, a normally de-energized stick relay for each section, means for energizing each stick relay while a train moving in the said one direction but not in the other occupies the associated section, means operating when each stick relay is energized to remove the associated line relay from its control of the line relay for the section next in the rear, a coding device located at the junction of each two adjacent sections and comprising a normally de-energized motor as well as two contacts operated thereby in accordance with two different codes, means operating when a section is occupied by a train to energize the motor for the coding device at each end of the section, and means for supplying train governing current to the rails of each section through one contact of an associated coding device when the associated line relay is energized and through the other contact of such device when the associated line relay is open and the associated stick relay is closed.

23. In combination, a track section, a transformer connected to the rails adjacent each end of said track section, means for normally supplying uninterrupted alternating current to the rails through one of said transformers, means operating when said track section is occupied by a train for supplying uninterrupted or interrupted alternating current to one said transformer according to traffic conditions beyond said track section in one direction and to the other said transformer according to traffic conditions beyond said track section in the other direction.

In testimony whereof I affix my signature.
HERBERT A. WALLACE.
